UNITED STATES PATENT OFFICE

WILLIAM ALEXANDER, OF GLASGOW, SCOTLAND

CENTRIFUGAL SEPARATOR

Application filed January 22, 1932, Serial No. 588,144, and in Great Britain December 31, 1931.

The invention relates to centrifugal separators in which gas, vapour or steam has a vertical or rotary motion, in a separating chamber and by the action of centrifugal force suspended impurities, whether liquid or solid, are thrown out to the sides of said chamber.

More particularly the invention relates to separators of the type in which the gas discharge pipe is arranged substantially coaxial with the separating chamber and is disposed to lead the discharged gas away from the inlet end of said chamber.

In the following description the term "gas" is intended to include any gas, vapour or steam; and the term "dust" is intended to include any impurities to be removed from the "gas".

In the centrifugal separator according to the invention, whether of down-flow or up-flow type, the separating chamber is provided with a dust channel or channels extending along the side of the separating chamber and formed on the inner side, i. e., the side adjacent to the chamber, with perforations or with a longitudinal slot or slots through which dust passes from the separating chamber into the channel or channels.

The dust passing into the dust channel or channels falls to the lower part thereof, instead of falling vertically from the separating chamber into a hopper or dust collecting vessel of comparatively large horizontal section situated below the separating chamber as heretofore.

The provision of a dust channel or channels, by enabling the usual dust hopper to be dispensed with, in most cases results in a separator of smaller and cheaper construction than a separator with the usual hopper. Also, the internal surface of the channel or channels being vertical or having a steep slope, there is less deposit and building up of dust on such surface than on the horizontal or inclined surfaces of a hopper, especially when the dust is of a sticky nature. Further, by the provision of an access opening at the top of the channel or each channel the internal surface may be more easily cleaned than the larger and less readily accessible

internal surfaces of a hopper fitted with an inspection opening.

In the drawing Fig. 1 is a vertical section and Fig. 2 a part plan part horizontal section of a vaneless down-flow separator according to the invention.

Fig. 3 is a vertical section of the upper part of a vanned down-flow separator.

Fig. 4 is a vertical section and Fig. 5 a part plan part horizontal section of a vertical up-flow separator.

The separating chamber 1, shown in the drawing, is of substantially circular cross section. 2 denotes the gas supply pipe (or pipes) opening into an admission chamber 3 adjoining one end of, and having communication with, the separating chamber. 4 denotes a comparatively narrow dust channel extending along the side of the separating chamber. At the top of the dust channel 4 there is an access opening adapted to be closed by a cover 5. At the lower end 6 the channel 4 converges to a narrower pipe form, a flange being provided for connection to a dust box or a dust pipe for leading the dust to any desired point. In the inner side of the dust channel 4 there are perforations or slots 7 for allowing the dust that is thrown out to the sides of the separating chamber 1 to pass into the dust channel where it gravitates to the channel outlet. A partition 8 partially isolates the admission chamber 3 from the separating chamber 1, and is encircled by a substantially annular passage 9, so that gas may flow with a circumferential component of velocity from the admission chamber 3 to the separating chamber 1. The inner end 11 of the gas discharge pipe 10 is coaxial or nearly coaxial with the separating chamber 1 and is situated at or near the opposite end of the separating chamber from the inlet end. The discharge pipe 10 does not extend through the core of the vortex and the gas flow in this pipe is in the direction away from the inlet end of the separating chamber. At or near the inner end of the discharge pipe is a flange 12 of straight, bent or curved cross section.

In the down-flow separator illustrated in Figs. 1 and 2 the gas entering the admission

chamber 3 from the tangentially disposed supply pipe 2 has a circumferential component of velocity, so that the gas entering the separating chamber 3 has also such a velocity component. The annular passage 9 is shown as having no guide vanes, but there may be provided inclined vanes extending across this passage and serving to impart a circumferential component of motion to the gas flowing into the separating chamber. When such vanes are provided, the gas supply pipe 2 may be situated nearer to the centre line of the separating chamber than is shown in plan in Fig. 2, or the gas supply pipe may lead into the top of the admission chamber, as shown in Fig. 3. The partition 8 and the flange 12 may be dispensed with, if desired. An aperture or apertures 13 in the side of the discharge pipe will allow any small percentage of dust that may descend into the chamber 14 to pass immediately into the gas discharge pipe.

The lower part of the vaned down-flow separator illustrated in Fig. 3 is of the same construction as the vaneless form shown in Fig. 1.

Referring to Figs. 4 and 5, the annular passage 9 of the up-flow separator is divided by inclined guide vanes which cause the gas to enter the separating chamber with the necessary circumferential component of flow.

The action of the separators will be readily understood. The gas flows with a whirl through the annular passage 9 into the separating chamber 1 and leaves at or near the opposite end of the chamber by the axial pipe 10 to which the flow converges. Throughout the unobstructed separating chamber 1 the motion of the gas is of true vortical stream-line nature, and free from eddies. Suspended dust carried to the outside of the vortex and entrained by the gas is expelled through the apertures 7 into the dust channel 5 and falls to the lower end 45 of the channel whence it is easily removed.

In the down-flow separators of Figs. 1, 2 and 3, any small percentage of dust that falls past the apertures 7 into the chamber 14 cannot build up in this chamber 14 but is entrained with the gas which passes from the chamber 14 through the apertures 13 to the interior of the gas discharge pipe.

What is claimed is:—

1. A centrifugal dust separator comprising an upright cylindrical casing including a gas admission chamber, a pipe supplying gas to said admission chamber, a vortical separating chamber coaxial with said admission chamber, a gas discharge pipe coaxial with both said chambers and projecting into said separating chamber, a partition partially isolating said separating chamber and affording an annular gas passage leading from said admission chamber to said separating chamber whereby there is set up in the gas enter-

ing said separating chamber through said passage a free vortex motion about a vertical axis, said separating chamber being bounded by a smooth vertical cylindrical wall and wholly free from internal obstructions from the axis to the periphery for that part of said separating chamber between said passage and said discharge pipe, said discharge pipe being shaped and positioned so that there is no gas flow along its outer surface towards its inner end, said discharge pipe discharging all the gas admitted to the separator, at least one external dust channel located alongside and extending the entire vertical length of said separating chamber, said channel extending over only a part of the circumference of said separating chamber, said channel communicating with said separating chamber by at least one small dimensioned aperture in the side of said channel, said aperture permitting passage of dust expelled from said separating chamber by centrifugal force, said channel having no gas current therethrough, and having no direct gaseous communication with said first mentioned pipe, said channel having a dust outlet at its lower end spaced in a direction parallel to the axis of the vortex and away from said aperture.

2. A centrifugal dust separator as claimed in claim 1 in which the annular gas passage is fitted with inclined vanes.

3. A centrifugal dust separator as claimed in claim 1 having at least one tangentially disposed gas supply passage.

4. A centrifugal dust separator as claimed in claim 1 in which the gas discharge pipe is provided with at least one aperture in its side for the escape of dust from the lower end of the separating chamber.

In testimony whereof I have signed my name to this specification.

WM. ALEXANDER.
